UNITED STATES PATENT OFFICE.

GEORGE J. TALBOT, OF NEW BRITAIN, CONNECTICUT, ASSIGNOR TO THE BUOL MACHINE COMPANY, OF NEW BRITAIN, CONNECTICUT, A CORPORATION OF CONNECTICUT.

AUTOMATIC SASH FASTENER.

Application filed November 16, 1926. Serial No. 148,635.

This invention relates to hardware and particularly to window sash fasteners.

An object of this invention is a simple and efficient sash fastener of such a character that when the window is closed, the fastener is automatically operated.

According to the invention, there is provided on one window sash a spring-impelled rotary fastener lever which engages a keeper 10 on the other window sash to fasten the window. A slidable detent is provided which has a projecting portion arranged in the path of the operating handle of the latch lever so that rotation of the latch lever from 15 its fastening position slides the detent. Means are provided for elevating a portion of the detent when thus slid into the path of the latch lever to prevent rotation thereof under the influence of its spring, and means 20 are provided for holding the detent in this position. Associated with a keeper is a trip member which, when the sashes are moved to close the window, releases the detent, thereby allowing the latch lever to rotate under 25 the influence of its spring into fastening relation to the keeper.

Other objects, novel features and advantages of the invention will be apparent from the following specification and accompanying 30 drawings, wherein

Figure 1 is a perspective view of a pair of window sashes equipped with a fastener embodying the invention, the sashes being in the position assumed when the window is 35 partly open;

Fig. 2 is a similar view with the window closed and the fastener in locking position;

Fig. 3 is a section on the line 3-3 of Fig. 1;

Fig. 4 is a section on the line 4-4 of Fig. 2;

Fig. 5 is a plan view of the latching lever and detent;

Fig. 6 is a bottom view thereof; and

Fig. 7 is a section on the line 7-7 of Fig. 5.

10 designates the sash of the lower window and 11 designates the sash of the upper window. To the sash 10 is secured a base 12, the central portion of which is recessed as at 13 and provided with lugs 14. Extending through an aperture in the top of the base 12 and into the recess is a hub 15. A rivet 16 passes through an aperture in the

latch lever 17 and through the hub 15. A 55 plate 18 rests against the end faces of the lugs 14 and the under face of the hub 15, this plate being held in position by riveting the end of the rivet 16 over the plate 18. The latch lever 17 is thus rotatably mounted 60 upon the base 12. A conical spring 21 has one end arranged in a notch in the hub 15 and the other end passed around a stud 22 projecting from the base 12. This spring tends normally to hold the latch lever 17 65 with its handle 23 engaging the stop 24 on the base 12.

In the base 12 is provided a groove 25 in which is slidably mounted a detent 26. The detent 26 is provided with a shoulder 27 projecting above the edge of the groove in position to be engaged by the handle 23 when the latch lever is rotated out of latching position. Such engagement slides the detent in its groove toward the other sash. At the 70 end of the detent is provided a hook 28 which, when the detent is thus slid, drops over the end to the bottom of the groove by gravity and fastens the detent against movement in the opposite direction. The 75 detent is provided with a slot 29 through which extends a pin 30. The arrangement of the slot 29 is such that, when the hook 28 overlies the edge of the base member 12, the upper edge of the opposite end of the 80 detent is arranged in the pathway of the handle 23, thereby preventing rotation of the lever 17 under the influence of the 85 spring 21.

On the sash 11 is mounted a keeper 31 90 which co-operates with the latch lever 17 to fasten the sashes 10 and 11 in window-closing relation. Pivotedly mounted on the keeper 31 and in alignment with the detent 26 is a trip member 32. When the sashes 10 95 and 11 are moved relative to each other to open the window, the trip member 32 rotates but when the sashes 10 and 11 are moved to close, the member 32 engages the end of the 100 detent 26 and lifts it to release the hook 28, thereby allowing the detent to be pushed rearwardly by the lever under the influence of the spring 21, the lever being continued into fastening relationship with the keeper 31. 105

It is understood, of course, that various structural modifications may be made in this

device without in any way departing from the spirit of the invention as set forth in the appended claims.

I claim:

5. 1. A sash latch comprising a base, a spring-impelled lever pivoted to said base for rotation about a vertical axis, a detent freely slideable horizontally and having a portion projecting into the path of said lever, means to position another portion of said detent in the path of said lever in one position of the detent, means other than said lever to hold said detent in said position, a keeper to co-operate with said lever, and means associated with said keeper for releasing said detent.
10. 2. A sash latch comprising a base member, a spring-impelled lever pivoted thereto to rotate about a vertical axis, a detent slideable horizontally and having a portion projecting into the path of said lever, means to elevate one end of the detent in one position thereof, a hook on said detent to hold it in this position, a keeper to co-operate with said lever, and means associated with said keeper for releasing said detent.
15. 3. A sash latch comprising a base, a spring-impelled lever pivoted to said base for rotation about a vertical axis, a detent slideable horizontally, a projection on said detent to be engaged by said lever to slide said detent in one direction, means to elevate a portion of said detent when thus slid into the path of said lever to prevent operation thereof under the influence of its spring, means to hold said detent in said position, a keeper to co-operate with said lever, and means associated with said keeper to release said detent.
20. 4. A sash latch comprising a base, a spring-impelled lever pivoted to said base for rotation about a vertical axis, a detent slideable horizontally in a groove in said base, a projection on said detent extending above the edge of said groove to be engaged by said lever to slide said detent in one direction, means to elevate a portion of said detent into the path of said lever to prevent rotation thereof under the influence of its

spring, means to hold said detent, in such position, a keeper to co-operate with said lever, and means associated with said keeper to release said detent.

5. A sash latch comprising a base, a spring-impelled lever pivoted to said base for rotation about a vertical axis, a detent slideable horizontally in a groove in said base, a projection on said detent extending above the edge of said groove, a pin and slot connection between said base and said detent whereby movement in said direction elevates a portion of said detent into the path of said lever to prevent rotation thereof under the influence of its spring, means to hold said detent in such position, a keeper to co-operate with said lever, and means associated with said keeper to release said detent.

6. A sash latch comprising a base, a spring-impelled lever pivoted to said base for rotation about a vertical axis, a detent slideable horizontally in a groove in said base, a projection on said detent extending above the edge of said groove, a pin and slot connection between said base and said detent whereby movement of said detent in said direction elevates a portion of the detent into the path of said lever to prevent rotation thereof under the influence of said spring, a hook on said detent to engage the end of said groove, a keeper to co-operate with said lever, and a trip member pivotally associated with said keeper to release said detent.

7. In combination a spring impelled rotatable lever, a freely slideable detent having a projection to be engaged by said lever to slide said detent in one direction, means to project another portion of said detent when thus slid into the path of said lever to prevent operation thereof under the influence of its spring, means other than said lever to hold said detent in position, a keeper to cooperate with said lever and means associated with said keeper to release said detent.

In testimony whereof, I have signed my name to this specification.

GEORGE J. TALBOT.

CERTIFICATE OF CORRECTION.

Patent No. 1,651,048.

Granted November 29, 1927, to

GEORGE J. TALBOT.

It is hereby certified that error appears in the printed specification of the above numbered patent requiring correction as follows: Page 1, line 9, for the word "fastener" read "latch"; line 73, for the word "latching" read "fastening"; and that the said Letters Patent should be read with these corrections therein that the same may conform to the record of the case in the Patent Office.

Signed and sealed this 27th day of December, A. D. 1927.

Seal.

M. J. Moore,
Acting Commissioner of Patents.
